UNITED STATES PATENT OFFICE.

WILLIAM W. FRY, OF LOS ANGELES, CALIFORNIA, ASSIGNOR OF ONE-HALF TO ROBIN-
SON PACKER COMPANY, OF TULSA, OKLAHOMA, A CORPORATION OF OKLAHOMA.

PACKER HEAD.

Application filed August 5, 1926. Serial No. 127,372.

This invention relates to improvements in packer heads to be attached to strings of casing, to be used in the casing of oil wells or the like, which strings are inserted in casings of 5 larger diameter.

One of the objects of the invention is to provide a device of this character with means to be engaged by an inserting or extracting tool, so that the string of casing to which the 10 packer head is attached may be raised or lowered through the instrumentality of the tools, at the will of the operator.

Another object of the invention is to furnish a device of this character, adapted when 15 the string of casing is set, to securely pack the space between the smaller casing and larger casing whereby any oil, gas or water can only issue from the well by passing through the packer head.

20 A further object is to furnish such a device with an annular beveled face at its upper end, designed to function as a seat for a valve, when the device is employed as a "flow" packer. When the packer head is inserted 25 in the well, a flow pipe with a valve surrounding the same may be inserted in the well and lowered to the point where the valve engages the beveled face on the packer head, and as a result of this, all fluid in the larger casing 30 below, will flow upward through the small pipe, producing a "nozzle" effect, and thus obtaining a higher elevation of the fluid in the hole, from the pressure below.

35 A still further object is to provide a packer head with means at its upper end to be automatically engaged or disengaged by an inserting or extracting tool, after the packing head has been set in position. Usually, in the course of sinking a hole, the operator finds it 40 necessary, at certain times, to under-ream, and at such times, he must pull back the string of casing to permit this. Should the operator desire to move the string of casing after he has once set it in the well, the extracting tool is lowered until it engages the 45 recesses at the upper portion of the packer head, and when the operator lifts on the packer head, it releases the packing from the outer casing, so that the string of casing may 50 be raised. The packer head, forming the subject matter of the present invention, readily permits such an operation to take place.

Another object of the invention is to provide a packer head of simple and inexpensive

construction which may be used indefinitely 55 without liability of getting out of order.

With the foregoing objects outlined and with other objects in view which will appear as the description proceeds, the invention consists in the novel features hereinafter described in detail, illustrated in the accompanying drawing, and more particularly pointed out in the appended claims.

Referring to the drawing:

Fig. 1 is a vertical sectional view of a well 65 with the improved packer head arranged at the upper end of the casing which is located in the casing of the well.

Fig. 2 is an enlarged vertical sectional view of the upper portion of the casing and the 70 packer head.

Fig. 3 is a horizontal sectional view taken on line 3—3 of Fig. 2.

In the drawing, 1 designates the well casing in which is located the casing 2, screwed 75 at its upper end, as shown at 3, to the reduced skirt 4 of the enlarged sleeve 5, which forms the lower part of the telescopic packer head. The upper end of the sleeve 5 is threaded at 6 to a ring 7, the latter being provided with 80 a plurality of recesses 8, each of which has a downwardly and outwardly extending surface 9, and a horizontal surface 10.

Slips 11 are arranged in the recesses 8, and each slip is of triangular formation in vertical section, and provided on its inner surface with teeth 12, which cooperate with teeth 13 on the inner sleeve 14 of the packer head.

This sleeve has an outwardly extending flange 15 at its lower end which abuts against 90 the collar 7 when the packer head is lifted, and bears the weight of the string of casing 2. The upper end of the sleeve is threaded at 16 to the upper portion 17 of the packer head. The lower surface 18 of the part 17, 95 and the upper surface 19 of the collar 7, form abutments or shoulders against which the rubber packing rings 20 bear; these packing rings surrounding the sleeve 14 and being adapted when the surfaces 18 and 19 move 100 toward each other, to expand outwardly against the inner surface of the casing 1 for packing off oil, gas or water.

The part 17 of the packer head is provided with an internal annular recess 21 having a 105 downwardly and inwardly extending curved face 22 and a horizontal face 23. An inverted channel 24 merges into the face 23 and is

adapted to receive projections on the slips of the inserting or extracting tool not shown, for the purpose of preventing splitting of the part 17, due to wedging action by the inserting or extracting tool.

The upper end of the part 17 is provided with an internal annular beveled surface 25 adapted, when the device is used as a "flow" packer to function as a valve seat for a valve 10 26, the latter being fixed on a narrow pipe 27 which may be lowered into the well for the purpose of raising the fluid under the pressure existing in the well.

The packer head and the string of casing 15 2, when the pipe 27 and valve 26 are not in the well, may be raised or lowered by a special tool, which is not illustrated herein. This tool is designed to engage the recess 21, and when the string of casing has been lowered to the bottom of the well, the sleeve 5 of the packer head will be halted, but the sleeve 14 with the inserting tool will continue to lower under the influence of the weight of the tool, and this will cause the rubber packing 20 to expand against the casing 1. During this expansion, the slips 11 ride over the teeth 13 of the sleeve 14, and after the parts 14 and 17 have reached the maximum lowered position, these slips will interlock with 25 the teeth 13 and prevent the sleeve 14 from rising under the influence of the rubber packing 20, after the weight of the tool has been released from the part 17. Consequently, the packing will remain expanded after the tool 30 is withdrawn and will thus pack the well.

When it is desired to raise the string of casing 2 and the packer head, the extracting tool may be again lowered into the well until it engages the recess 21, and then, by agitating the part 17, the slips 11 are caused to disengage the sleeve 14, so that the packing 20 is released and the flange 15 comes into engagement with the collar 7 for lifting the string of casing and packer head by the tool.

45 What is claimed and desired to be secured by Letters Patent is:—

1. A packer head including a lower large

sleeve adapted to be connected to a string of casing, a collar detachably connected to the large sleeve and having a plurality of recesses therein, an upper annular member, an inner sleeve secured to the upper member and having a flange at its lower end to engage said collar, a resilient packing ring surrounding the inner sleeve, radially movable slips arranged in said recesses, and coacting teeth on the slips and inner sleeve for locking the sleeves in various adjusted positions.

2. A packer head including an upper annular member, an inner sleeve having its upper end connected to the upper member, a fixed flange on the lower end of the inner sleeve packing rings surrounding the sleeve and bearing against said upper member, a collar engageable with said flange surrounding said sleeve and bearing against said packing rings, said collar being provided with recesses, each recess having a downwardly and outwardly extending surface and a substantially horizontal surface, radially movable slips arranged in said recesses, each slip being substantially triangular in vertical section, cooperating teeth on said sleeve and slips for locking the collar in various adjusted positions to said sleeve, and an outer sleeve having its upper end detachably connected to said collar and provided at its lower end with means of attachment for a well casing.

3. A packer head including a sleeve adapted to be connected to a string of casing, a member detachably connected to said sleeve having a recess therein, an upper annular member, an inner sleeve secured to the upper member and adapted to engage the first mentioned member, a resilient packing ring surrounding the inner sleeve, said recess having a downwardly and outwardly extending surface, a radially movable slip arranged in said recess and co-acting with the inner sleeve for locking the sleeve in various adjusted positions.

WILLIAM W. FRY.
